UNITED STATES PATENT OFFICE

GEORGE R. McDERMOTT, OF MOUNT VERNON, OHIO, ASSIGNOR TO THE CHAPMAN-STEIN FURNACE COMPANY, OF MOUNT VERNON, OHIO, A CORPORATION OF OHIO

RECUPERATIVE SOAKING PIT

Application filed April 4, 1928. Serial No. 267,238.

The invention relates to soaking pits, more particularly of the type wherein the air for combustion is preheated by passing it through a recuperator heated by the waste gases exhausted from the pit, and the primary object of the invention is to provide a distribution of the heating gases in the soaking pit which will secure uniform heating conditions therein.

10 Further objects and advantages of the invention will be in part obvious and in part specifically referred to in the description hereinafter contained, which, taken in conjunction with the accompanying drawings, 15 discloses a preferred embodiment thereof; such embodiment, however, is to be considered merely as illustrative of its principles. In the drawings—

Fig. 1 is a vertical section through a furnace constructed in accordance with the invention, and

Fig. 2 is a transverse section taken on line A, B, C, D, and E of Fig. 1.

In the illustrated form of the invention I have shown a soaking pit 1 having a removable cover 2 and a bottom 3, adapted to receive ingots 4 in the usual manner. The air and gas for combustion come in respectively through one or more air conduits 5 and gas conduits 6, which latter mix the gas with the air prior to their entry into the soaking pit, the combustible mixture being admitted into the soaking pit at the upper part of one of its side walls in such manner that the gases of combustion first pass across the pit over the tops of the ingots and then turn downwardly as indicated by the arrows in the drawing, and a portion of such gases return in a horseshoe shaped path, until they pass out of the pit through one or more exhaust passages 7 located at the bottom of the same sidewall.

40 The exhaust gases then pass through a suitable heat interchanger or recuperator 8, the illustrated construction being substantially as shown in the U. S. patent to Stein No. 1,404,721, January 24, 1922, in which type of recuperator the waste gases pass in a zig-zag path through the recuperator from top to bottom and are finally led into a collecting

flue 9 controlled by a damper 10, and communicating with the stack flue 11.

The air for combustion passes up vertically through a recuperator of the above type to a gathering chamber 12 located at the top of the recuperator and communicating with the air conduits 5 above mentioned.

In accordance with the present invention a portion of the heating gases is led through the soaking pit 1 in a horseshoe path and exhausted through passages 7 as above described, and another portion of the heating gases is diverted therefrom by means of one or more exhaust ports 13, preferably located near the bottom of the pit, and in or near the sidewall thereof which is opposite to the sidewall in which the above mentioned exhaust passages 7 are located. In the illustrated form of the invention auxiliary exhaust ports 13 are located on opposite sides of a door 14 in the front wall of the furnace, and further auxiliary exhaust ports 15 are also provided in the opposite sidewalls of the pit near its front corners, the exhaust ports 13 and 15 above mentioned communicating with exhaust gas conduits 16 running through the sidewalls of the soaking pit.

The heating gases thus will pass into the soaking pit and across the tops of the ingots 4, until they turn downwardly to pass along the ingots, and at this latter point the stream of heating gases will split, a portion of such gases passing out through the ports 13 and 15 above mentioned while another portion passes back along the bottom of the pit and out through exhaust passages 7. It is found that the above distribution of the heating gases in the soaking pit makes it possible to heat the ingots more uniformly, avoiding dead spots or points of overheating in the pit. It will be noted that with the specific arrangement of points and exhaust passages above described, the gases are exhausted at or near the four corners of the soaking pit.

As above stated, the exhaust gases passing out through passages 7 preferably are led through the recuperator 8, to which the conduits 16 also may be connected. I prefer to connect the conduits 16 to the recuperator at points where the suction is somewhat greater

as compared to the point of entry of the gases issuing from ports 7. In the illustrated form of the invention the exhaust gases coming into the recuperator from passages 7, make three horizontal passes across the recuperator at different levels, and the conduits 16 enter the recuperator at the chamber 17, which is interposed between the second and third passes, and subjects the conduits 16 to a somewhat greater suction. The major portion of the spent heating gases however, usually will pass out of the soaking pit through passages 7. The proportion of flow of spent gases through the above paths may be regulated by means of dampers 18 (Fig. 2) associated with conduits 16, and further dampers 19 (Fig. 1) controlling the flow through the recuperator of the gases passing out of the pit through passages 7.

20 While a specific embodiment of the invention has been disclosed, it is obvious that many changes may be made therein without departing from its principles as set forth in the appended claims.

25 I claim:

1. In combination, a soaking pit, means for admitting a combustible mixture at one side thereof and projecting the resulting gaseous stream across the soaking pit to the opposite side thereof, said pit having one or more exhaust passages for the heating gases near the same side thereof which cause a portion of said stream to return across the pit in a horseshoe shaped path and pass out of the pit through said passages, and one or more auxiliary exhaust ports located adjacent the opposite side of the pit which divert a portion of said gaseous stream from said horseshoe shaped path.
2. In combination, a soaking pit, means for admitting a combustible mixture at one side near the top of the pit and projecting the resulting gaseous stream across the soaking pit to the opposite side thereof, said pit having one or more exhaust passages for the heating gases near the same side and near the bottom of the pit which cause a portion of said stream to return across the pit in a horseshoe shaped path and pass out of the pit through said passages, and one or more auxiliary exhaust ports located near the opposite side of the pit which divert a portion of said gaseous stream from said horseshoe shaped path and near the bottom thereof.
3. In combination, a soaking pit, means for admitting a combustible mixture at one side thereof and projecting the resulting gaseous stream across the soaking pit to the opposite side thereof, said pit having one or more exhaust passages for the heating gases near the same side thereof which cause a portion of said stream to return across the pit in a horseshoe shaped path and pass out of the pit through said passages, one or more auxiliary exhaust ports located adjacent the op-

posite side of the pit which divert a portion of said gaseous stream from said horseshoe shaped path, and a heat interchanger receiving the gases exhausted both from said passages and said ports.

4. In combination, a soaking pit, means for admitting a combustible mixture at one side thereof and projecting the resulting gaseous stream across the soaking pit to the opposite side thereof, said pit having one or more exhaust passages for the heating gases near the same side thereof which cause a portion of said stream to return across the pit in a horseshoe shaped path and pass out of the pit through said passages, one or more auxiliary exhaust ports located adjacent the opposite side of the pit which divert a portion of said gaseous stream from said horseshoe shaped path, and means for regulating the proportion of gases flowing through said passages and ports.

5. In combination, a soaking pit, means for admitting a combustible mixture at one side thereof, said pit having one or more exhaust passages for the heating gases near the same side thereof, one or more auxiliary exhaust ports located adjacent the opposite side of the pit, a heat interchanger of the suction type connected both to said passages and said ports, the ports being connected to the heat interchanger at a point where the suction is greater than with respect to the passages.

6. In combination, a soaking pit, means for admitting a combustible mixture at one side thereof, said pit having one or more exhaust passages for the heating gases near the same side thereof, one or more auxiliary exhaust ports located adjacent the opposite side of the pit, a recuperator of the suction type wherein the heating gases pass through from top to bottom, said passages leading to the upper part of the recuperator, and conduits connecting said auxiliary ports to a point in said recuperator at a lower level.

7. In combination, a heat interchanger, a soaking pit, means for admitting a combustible mixture thereto at the top of the pit, said pit having one or more exhaust passages for the heating gases located near the bottom of the pit at one end thereof and which are connected to said heat interchanger to pass a portion of the heating gases therethrough, and means for withdrawing another portion of the heating gases from one or more points near the bottom of said pit at the opposite end thereof and by-passing the same around a portion of the heat interchanger.

8. In combination, a soaking pit, means for admitting a combustible mixture at one side near the top of the pit and projecting the resulting gaseous stream across the soaking pit to the opposite side thereof, said pit having exhaust passages for the heating gases near the bottoms of the corners of the same side

which cause a portion of said stream to return in a horseshoe shaped path and pass out of the pit through said passages, and said pit also having auxiliary exhaust ports located near the bottoms of the corners at the opposite side of the pit which divert a portion of said gaseous stream from said horseshoe shaped path.

In testimony that I claim the foregoing, I have hereunto set my hand this 28th day of March, 1928.

GEORGE R. McDERMOTT.
